J. C. Whitney Catalog No. 540J, p. 106, Rear Spoiler-Air Deflector for Trucks, center right side of page.

Primary Examiner—James M. Gandy
Attorney, Agent, or Firm—Janet Peyton Schafer[57] **CLAIM**

The ornamental design for a vehicle air deflector, as shown and described.

DESCRIPTION

FIG. 1 is a perspective view of a vehicle air deflector showing my new design in position of use on a vehicle which is fragmentarily shown by broken lines for illustrative purposes only and forms no part of the claimed design;

FIG. 2 is a left side elevational view thereof with the right side being a mirror image;

FIG. 3 is a top plan view thereof;

FIG. 4 is a rear elevational view thereof;

FIG. 5 is a bottom plan view thereof; and,

FIG. 6 is a front elevational view.
